WASHING MACHINE

Gerald B. Fox, Troy, Ohio, assignor to The Hobart Manufacturing Company, Troy, Ohio, a corporation of Ohio

Application January 13, 1939, Serial No. 250,793

6 Claims. (Cl. 299—70)

This invention relates to washing machines and more particularly to a washing machine providing for the complete cleansing and rinsing of dishes, glasses, and other utensils.

In a washing machine of this character it has been the practice to uniformly distribute the wash and rinse fluids to all parts of the machine by means of rotatable wash and rinse arms adapted to be rotated by the reaction forces of the fluids discharged through suitable spray openings provided in the arms. To maintain the rinse arms in a non-interfering position relative to the discharge openings of the wash arms it has also been the practice to mount the rinse arms for rotation as a unit with the wash arms. It has, accordingly, been necessary for the reaction forces of the rinse fluid to rotate the entire unit including the wash arms which comprise relatively large heavy castings formed integral with a central hub member. The rinse fluid is supplied from some external source such as a city water system and the reaction forces of the rinse fluid are usually considerably less than those of the wash fluid which is discharged in a relatively much larger quantity from the wash arms. Thus it has been found that in certain cases such as when the pressure of the rinse supply source falls too low or too long a time is permitted to elapse between the shutting off of the wash fluid and the turning on of the rinse fluid with loss of rotational momentum, the reaction forces of the rinse fluid may be insufficient to cause satisfactory operation of the rinse arms.

A primary object of the invention, accordingly, is the provision of a washing machine in which the rinse distributor is rotatable entirely independently of and out of contact with the wash distributor and in which the wash distributor drives the rinse distributor during the washing operation to effect rotation of both distributors with the rinse distributor maintained in predetermined positioning such that the rinse arms do not interfere with the discharge sprays of the wash arms.

It is a further object to provide such a device in which the rinse arm is arranged for operation during rinsing entirely independent of and out of contact with the wash arm so that no interference with or impediment to the free rotation of the rinse arm is caused by the wash arm.

Other objects and advantages will be apparent from the following description, the appended claims, and the accompanying drawings, in which—

Fig. 1 is an elevational view, partly broken

away and partly in section, of a washing machine provided with a rotatable fluid distributing device constructed in accordance with the present invention;

5 Fig. 2 is a plan view of the rotatable fluid distributing mechanism;

Fig. 3 is a view partly in section and partly in elevation taken along the line 3—3 of Fig. 2 with the rinse arms rotated into the plane of the 10 wash arms;

Fig. 4 is a detail view of one of the clutch members interposed between the wash arm and rinse arm;

Fig. 5 is a sectional view taken along the line 5—5 of Fig. 3;

Fig. 6 is a broken, fragmentary elevational view of a washing machine provided with both upper and lower rotary fluid distributing devices embodying the present invention; and

20 Fig. 7 is a fragmentary view, partly in elevation and partly in section, showing the construction of the upper distributing device illustrated in Fig. 6, the view being taken substantially the same as Fig. 3 with the rinse arms rotated into the 25 plane of the wash arms.

Referring to the drawings which illustrate preferred embodiments of the invention, and to Fig. 1 in particular, there is shown a supporting framework 10 upon which is mounted a tank 11. A semicylindrical cover 12 adapted to enclose a utensil carrying rack 13 slidably supported on track members 14 is positioned adjacent the upper end of the tank. The cover 12 is suitably mounted on the tank for movement to an open position providing for the ready insertion and removal of the rack 13, and to the closed position shown. The tank is provided with a sump 15 communicating with a centrifugal pump 16 driven by motor 17 and adapted to circulate the wash fluid 30 contained within the tank upwardly through a pipe 18 into a rotatable wash distributor 19 from which it is forcibly expelled to effect a cleansing of the utensils contained in the rack 13. A fitting 20 provided with a rotary valve 21 is interposed in the pipe 18 to provide for stopping and controlling the flow of wash fluid to the rotary distributor 19.

40 A pipe 22 provides for introducing fresh rinse water heated to a desired degree of temperature into the interior of the washing machine. As shown the pipe 22 has a branch 23 which connects with a lower rinse distributor 24 and a branch 25 which extends upwardly into the space enclosed by the cover 12 and connects with a plurality of stationary rinse nozzles 26 adapted to

spray the rinse fluid downwardly upon the articles contained within the rack 13.

An overflow pipe 30 connected to a drainage pipe 31 communicates with the interior of the housing and provides for withdrawing grease, 5 scum, and other matter which floats upon the top of the wash liquid contained within the tank and is caused to rise above the outlet to the overflow pipe upon introduction of the rinse fluid. Sieves 32 positioned above the sump 15 provide for removing any coarse particles of food or the like from the wash fluid before it is recirculated through the wash distributor 19. The drainage pipe 31 communicates with the sump 15 and provides for draining the washing fluid from the interior of the tank. It is to be understood that suitable means, controlled exteriorly of the tank, are provided for effecting the operation of the motor 17 to cause circulation of the wash fluid and for introducing a rinse fluid into the machine 10 after a washing operation.

Both the wash distributor 19 and the lower rinse distributor 24 are adapted to be rotated by the reaction forces of the fluids expelled therefrom and the arrangement is such that the rinse distributor can rotate independently of the relatively heavy wash distributor to facilitate the operation of the rinse distributor and provide for satisfactory rotation thereof even though the reaction forces of the rinse fluid are relatively weak and would be insufficient to effect a satisfactory rotation of both the rinse and wash distributors. Provision is made, however, for locking the distributors together for concurrent rotation in unison upon operation of the wash distributor to prevent the arms of the rinse distributor from interfering with the distribution of fluid from the lower positioned wash distributor. The two distributors are rotatably mounted on a fitting 35 that is supported by the pipe 18 which supplies wash fluid from the pump 16. The fitting 35 is provided with a laterally extending nipple 36 that is attached to an elbow 31 that connects with the pipe 18 above the valve fitting 20. The bottom of the fitting 35 is provided with a hollow upstanding boss 38 provided with an annular shoulder 39 and communicating with a nipple 40 adapted to be connected to the rinse branch pipe 23. A hollow stem member 41 is removably mounted within the boss 38 with its bottom resting upon the shoulder 39 and its upper end extending exteriorly of the fitting 35 through a circular opening 42 defined by an upstanding cylindrical lip 43. The stem 41 is mounted concentrically of the opening 42 and is held in vertical position so that the wash and rinse distributors rotate in a substantially horizontal plane within the tank 11. A key 44 serves to maintain the stem 41 within the boss 38 and additionally serves to prevent rotation of the stem relative to the fitting 35. As shown in Fig. 5 the boss 38 is provided with a laterally extending hollow, cylindrical portion 45 that communicates with an opening in the side wall of the fitting 35 and within which the elongated key 44 is received and extends exteriorly of the fitting. The key 44 is provided with an elongated tapered portion 46 that is adapted to engage a flattened portion 47 provided on the exterior wall of the stem 41. A nut 48 threaded on the exterior end 70 of the key 44 provides for moving the key outwardly to cause the tapered portion of the key to wedge against the flattened portion of the stem to securely lock the stem within the boss 38 and prevent rotation thereof. The elongated tapered

portion of the key is so proportioned that when the nut 48 is loosened and the key moved inwardly the stem 41 is freed from the key and may be readily removed from the boss 38.

The wash distributor 19 is mounted on the stem 41, and as shown comprises a central hub 50 adapted to fit over the stem and a pair of oppositely extending hollow arms 51 provided with spray outlets 52. The bottom of the distributor is formed with a depending cylindrical lip 53 adapted to surround the upstanding lip 43 of the fitting 35 and provide a non-frictional but effectively closed continuous passage from the interior of fitting 35 into the hollow arms of the distributor. The internal diameter of the lip 53 is slightly greater than the greatest external diameter of the lip 43 and has sufficient height to overlap lip 43 over a limited sliding movement of the wash distributor axially of the stem 41. The hub 50 is provided with an internal sleeve 54 constructed from a suitable non-corrosive bearing material and adapted to provide a bearing for the rotational and axial movement of the distributor on the stem 41. The wash distributor 15 normally occupies a lowered inoperative position in which the bottom of the hub 50 engages and rests upon the top of the upstanding boss 38 but is adapted to slide upwardly on the stem 41 in response to the introduction of washing fluid therein.

The ends of the arms 51 are closed by fittings 55 that are provided with angularly directed spray outlets 56 adapted to cause rotation of the distributor by the reaction of the wash fluid expelled under pressure therefrom. As shown, the angularity of the spray outlets 56 is adjustable within the limits of slots 57 adapted to cooperate with screws 58 threaded into the arms 51, and the fittings 55 are maintained in the adjusted 30 position by means of set screws 59.

The rinse distributor 24 is coaxially mounted on the stem 41 above the wash distributor and is supported for rotation independently of the wash distributor as mentioned above. As shown the rinse distributor comprises a hollow, substantially cylindrical casting 65 having upper and lower internal bosses 67 and 68 that fit on the stem 41 and provide a bearing for the rinse distributor. Two oppositely directed sleeve-like parts 69 communicate with the interior of the casting and support a pair of hollow rinse arms 70 which are received within the sleeve-like parts 69 and extend in opposite directions laterally of the distributor head 65. The rinse arms 70 are removably secured within the sleeves 69 by means of set screws 72 and are provided with a plurality of spray outlets 71 positioned in the side walls of the rinse arms and so arranged that the distributor is caused to rotate by the reaction forces of the fluid expelled therefrom. The outer ends of the rinse arms 70 are closed by plug-like members 73 that thread into the ends of the rinse arms and are provided with retaining clips 74 which hook around the rinse arms inwardly of the outermost spray outlets 71 and serve to prevent loss of the plug members when the plugs are unscrewed from the rinse arms. The rinse fluid is conducted to the rinse distributor by means of the hollow stem 41 which communicates with the nipple 40 and supply pipe 22 and is provided adjacent its upper end with a plurality of openings 75 that communicate with the interior of the distributor head 65 intermediate the upper and lower supporting bosses 67 and 68 thereof.

The upper end of the stem 41 is closed and the thrust load of the rinse distributor is sustained by an end bearing one portion of which is mounted upon the closed upper end of the stem. As shown a bolt 80 provided with an enlarged head 81 of suitable bearing material is threaded into the upper end of stem 41 until a shoulder 82 provided on the bolt in spaced relation to the head 81 engages the top of the stem. The boss 67 of the rinse distributor is provided with an upstanding externally threaded portion 83 and a cup-shaped cap member 84, partly broken away in Fig. 2, threads upon this portion and overlies the stem 41 and bearing bolt 80. A screw 85 threads through the cap 84 axially of the stem 41 and is provided at its inner end with a suitable bearing part 86 that is adapted to engage the head 81 of bolt 80 and support the weight of the rinse distributor thereon.

The vertical positioning of the rinse distributor axially of the stem 41 is such that a predetermined spacing is provided between the bottom of the rinse distributor and the top of the wash distributor when the latter occupies its inoperative position with the hub 50 resting upon the upstanding boss 38. This spacing permits a limited vertical movement of the wash distributor axially of the stem 41 when a wash fluid is introduced therein. As above mentioned, the wash distributor is adapted to slide on the stem in response to the introduction of the wash fluid, the hydraulic pressure of the fluid which is introduced upwardly under pressure causing the distributor to move upwardly on the stem until the top of hub 50 engages the bottom of the rinse distributor.

The upward thrust acting on the wash distributor by reason of the hydraulic pressure of the wash fluid introduced therein is transmitted to the rinse distributor upon movement of the wash distributor into engagement therewith and this thrust is taken by a slotted washer or key 87 that overlies the upstanding boss portion 83 of the rinse distributor and is received beneath the head 81 of the bolt 80. The bolt 80 and washer 87 thus serve as a thrust bearing which retains the rinse distributor in position on the stem 41 and limits the upward movement of the wash distributor. As shown in Fig. 2 the key 87 is circular in shape and the slot 88 is of just sufficient length and width to permit the key to slide past the shank portion of the bolt 80 to a central position relative to the stem 41 and the boss 83 where it locks the boss beneath the head 81 of the bolt. The size of the key 87 is such that it is normally maintained in its assembled position by the enclosing wall of the cap member 84. Upon unscrewing and removal of the cap member 84, however, the key may be readily slid from under the head of the bolt 80 to provide for the ready and rapid removal of the washing and rinsing distributors for cleaning or other purposes. The rinse distributor is thus mounted for free rotation and is maintained in a substantially fixed vertical positioning relative to the stem 41. This positioning may be adjusted within limits by rotating the bearing screw 85 which has threaded engagement with the cap member 84. As shown in Fig. 3 the tubular rinse arms 70 are relatively light in weight and the construction and mounting of the distributor is such that it will be readily rotated by reaction forces that are relatively weak as compared to those required for an effective rotation of the wash distributor.

The axial movement of the wash distributor in response to the introduction of fluid therein is utilized to make a locking connection between the rinse distributor and the wash distributor 5 upon operation of the wash distributor to cause unitary rotation of the two distributors with the rinse distributor maintained in a position in which it does not interfere with the distribution of fluid from the discharge openings of the wash distributor. As shown in Fig. 3 a clutch means adapted to provide a one way drive between the wash distributor and the rinse distributor upon upward movement of the wash distributor is interposed between the bottom of the rinse distributor and the top of the wash distributor and comprises a pair of cooperating clutch members 90 mounted upon annular seats provided on the bottom of casting 65 and the top of hub 50. The clutch is of the overrunning type and as best shown in Fig. 4 each of the members 90 comprises an annular member having a pair of flat portions 91 that rise gradually from the plane of the seat and terminate in vertically directed faces 92 which extend radially of the stem 40 at diametrically opposite points on the annular member. The vertically extending face portions 92 are so arranged that when the wash distributor is rotated and caused to move upwardly into engagement with the rinse distributor by the introduction of wash fluid into the former the faces 92 of the clutch part 90 carried by the wash distributor will engage the faces 92 of the rinse distributor clutch member and cause the two distributors to rotate as a unit. The angular positioning of the vertical faces 92 relative to the wash arms 51 and rinse arms 70, respectively, is such that the distributors are locked together with the arms in a non-interfering relationship. In the illustrated embodiment of the invention the distributors are locked together with their arms positioned approximately 90° apart as shown in Fig. 2. The clutch members 90 are secured to their seats by means of screws which extend through countersunk holes 93 provided in the portions of the members 90 that lie flat against the seats adjacent the vertical faces 92. The weight of the wash distributor is such that it falls by gravity to its lowered position in which the clutch members 90 are disengaged when the supply of wash fluid thereto is terminated. The rinse distributor is then free to rotate entirely independently of and out of contact with the wash distributor upon the introduction of a rinse fluid thereto. In Figs. 6 and 7 there is illustrated an embodiment of the invention in which rotary wash and rinse distributors having provision for rotation of the rinse arms independently of the wash arms and for locking the wash and rinse arms together upon operation of the wash arms to prevent interference with the discharge of the washing fluid are provided both above and below the rack that supports the articles to be washed and distribute the washing and rinsing fluids both upwardly and downwardly over the articles contained in the rack. The lower distributing unit which is designated generally by the reference numeral 110 is of a construction similar to that illustrated in Figs. 1 through 5 of the drawings and is mounted within the tank portion 111 below the article carrying rack 112 by means of branch pipes 113 and 114 which operatively connect the wash and rinse distributors with the wash fluid supply pipe 115 and the rinse fluid supply pipe 116 respectively in the manner here-

inabove described. A housing portion 118 provided with doors 119 extends upwardly from the tank portion 111 and encloses a washing chamber above the rack 112. The upper distributing unit 120 is mounted within the housing portion 118 above the rack 112 and is of a construction generally similar to that of lower unit 110.

As shown in Figs. 6 and 7 the upper unit 120 comprises a fitting 125 that is suitably supported adjacent the top of the housing portion 118 and rotatably supports a wash distributor 126 and a rinse distributor 127. A branch pipe 129 connects the fitting 125 with the wash supply pipe 115 and a branch pipe 130 connects the fitting 125 with the rinse supply pipe 116. The fitting 125 is of substantially the same construction as the fitting 35 shown in Figs. 1, 3 and 5 of the drawings and is provided with a downwardly extending discharge portion 135 that communicates with the wash fluid supply pipe 129 and with a downwardly extending hollow boss 136 that is positioned concentrically of the portion 135 and communicates with the rinse supply pipe 130. A hollow stem member 140 extends downwardly from the boss 136 and is normally secured within the boss by means of a tapered key 141 that corresponds with the key 44 in Figs. 3 and 5 and provides for removing the stem when desired for cleaning or other purposes. The stem 140 extends downwardly below the discharge portion 135 of the fitting 125 and rotatably supports the wash distributor 126 and the rinse distributor 127.

The wash distributor 126 is of a construction generally similar to that of the distributor 19 shown in Figs. 1 and 3 of the drawings and comprises oppositely extending wash arms 145 and a central hub 146 that is rotatably mounted on the stem 140 by means of a bearing sleeve 147. A cylindrical lip 149 extends upwardly in surrounding relation to the discharge portion 135 of fitting 125 and provides a non-frictional but effectively closed continuous passage between the interior of the fitting and the interior of the wash distributor. The height of the lip 149 is sufficient to maintain its overlapping relation with the discharge portion 135 throughout a limited movement of the wash distributor axially of the stem member 140.

The rinse distributor 127 is likewise of a construction generally similar to that of the rinse distributor 24 illustrated in Figs. 1, 2 and 3 of the drawings and comprises a distributing head 155 that is rotatably mounted on the lower end of the stem 140 by means of bearings 156 and 157 and carries the oppositely extending rinse arms 158 provided with spray nozzles 159. The rinse fluid is introduced into the rinse distributor by means of openings 160 which are provided in the stem member 140 between the bearings 156 and 157 and communicate with the hollow interior of the stem member. The thrust load of the rinse distributor and such portion of the downward thrust on the wash distributor as is transmitted thereto, is taken by means of an end bearing that is mounted on the lower end of the stem 140 and has a construction generally similar to the thrust bearing provided in the device of Figs. 1, 2 and 3. As shown, a bolt 165 is threaded into the lower end of stem 140 and is provided with an enlarged head 166 that fits over a slotted washer or key 167 that extends into supporting engagement with the under side of a depending boss 168 provided on the distributor head 155. The head 75

of the bolt which is made of suitable bearing material thus provides a thrust bearing that supports the rinse distributor against downward movement relative to the stem 140. A cap 170 threads on the exterior of the depending boss 168 and normally maintains the key 167 in supporting relationship with respect to the bolt 165 and boss 168 but provides for ready removal of the key when it is desired to remove the rinse distributor from the stem member.

To provide for releasably locking the rinse distributor to the wash distributor upon operation of the latter to effect joint rotation of the two distributors with the rinse arms maintained in a non-interfering position relative to the discharge of the washing fluid a pair of cooperating clutch members 175 are attached to the top of the rinse distributor 127 and to a bottom portion of the wash distributor 126 and are adapted to be engaged upon axial movement of the wash distributor towards the rinse distributor. As shown the clutch members 175 are of a construction similar to the clutch members 90 described above and are provided with radially directed vertically extending face portions 176 that cooperate to provide a one way drive between the wash distributor and rinse distributor to cause rotation of the latter in response to rotation of the former. The clutch members are secured to the distributors by means of screws 177 and the vertical faces 176 are so positioned that the distributors are locked together with the arms in a predetermined non-interfering relationship, this relationship being such in the illustrated embodiment that the distributors are locked together with the arms substantially 90° apart as in the device of Figs. 1 to 3.

To provide for rotation of the rinse distributor entirely independently of the wash distributor a means is provided for supporting the weight of the wash distributor and normally maintaining it in a raised position in which the cooperating clutch members 175 are disengaged and the rinse distributor is out of contact with the wash distributor. As shown in Fig. 7 the stem 140 is grooved to receive a C-shaped washer 180. This washer fits inside the bore of lower clutch member 175 and is thus retained in operative position. The washer 180 supports a sleeve 181 that is rotatably mounted on the stem and is slidably received within a recess 182 provided in the lower portion of the hub bearing sleeve 147. A coil spring 183 is positioned in the recess 182 above the sleeve 181 and is adapted to be compressed between the top of the recess and the sleeve. The sleeve 181 is keyed to the bearing sleeve 147 for rotation therewith by means of a projection 184 that extends inwardly from the upper clutch member 175 and is received within a vertically elongated slot 185 provided in the sleeve 181. To assure axial travel of the hub 146 and bearing sleeve 147 in unison the sleeve 147 is provided with an external shoulder 186 which engages and cooperates with an internal shoulder 187 provided on the hub. A washer 188 constructed from suitable bearing material is mounted on the washer 180 below the sleeve 181 and provides a bearing surface for taking the thrust load on the sleeve.

The strength of spring 183 is such that it will normally support the weight of the wash distributor 126 and maintain the distributor in the raised position illustrated in Fig. 7 in which the cooperating clutch members 175 provided on the wash and rinse distributors are disengaged. The rinse distributor is thus free to rotate entirely

independently of and out of contact with the wash distributor in response to the introduction of a rinse fluid therein, it being understood that the arrangement of the nozzles 159 is such that the reaction forces of the fluid expelled therefrom will cause rotation of the rinse arms. The strength of the spring 183 is also such, however, that when a wash fluid is introduced into the wash distributor the hydraulic pressure of the fluid which is introduced downwardly and under pressure will compress the spring and cause the wash distributor to slide downwardly upon stem 140 into engagement with the top of the rinse distributor. The cooperating faces 176 of the clutch members are thus caused to engage upon rotation of the wash distributor in response to the reaction forces of the fluid expelled from the angularly positioned nozzles 190 provided at the ends of the wash arms and lock the two distributors together for rotation in unison with the rinse arms maintained in a position in which they do not interfere with the discharge of the wash fluid. The portion of the downward thrust on the wash distributor that is not utilized in compressing the spring 183 is taken up by the end bearing 166 and washer 167 which, as mentioned above, support the rinse distributor against downward movement relative to the stem 140. When the supply of washing fluid is terminated the spring 183 returns the wash distributor to its raised position in which the clutch members 175 are disengaged and the rinse distributor is again free to rotate entirely independently of the wash distributor upon the subsequent introduction of a rinse fluid therein.

While the forms of apparatus herein described constitute preferred embodiments of the invention, it is to be understood that the invention is not limited to these precise forms of apparatus, and that changes may be made therein without departing from the scope of the invention which is defined in the appended claims.

What is claimed is:

1. In a washing machine of the character described, a pair of fluid distributing arms for distributing fluid to and upon the articles to be washed, a stem member, means for mounting said arms adjacent each other for independent rotation on said stem member with one of said arms being positioned inwardly of the other in the direction in which the fluid is projected, a driven member carried by and rotatable with the inner of said arms, a drive member carried by and rotatable with the outer of said arms, means for supporting said members respectively for movement relative to each other from an inoperative position leaving the arms free of contact with each other to an operative interengaging position, cooperating means on said drive and driven members for effecting the retaining of said inner arm in non-interfering relation with the fluid discharge from said outer arm during driving engagement therebetween, and means operable upon supply of pressure fluid to and rotation of said outer arm in the absence of supply of pressure fluid to said inner arm for effecting said relative movement of said drive and driven members to establish driving engagement therebetween.

2. In a washing machine of the character described, a stem member, a relatively heavy wash arm mounted on said stem and adapted to be rotated by the reaction forces of a wash fluid expelled from discharge openings provided in the arm, a relatively light weight rinse arm 75

mounted on said stem and also adapted to be rotated by the reaction forces of a rinse fluid expelled from discharge openings provided in said arm, means supporting said rinse arm for rotation entirely independently of and out of contact with said relatively heavy wash arm and in response to reaction forces that would be insufficient to cause effective rotation of the wash arm, normally inoperative means for establishing a driving relation between said wash and rinse arms and means operable in response to hydraulic pressure supplied to said wash arm for rendering said last mentioned means operative for locking said arms together to provide for rotation of the wash and rinse arms in unison with the rinse arm maintained in a predetermined non-interfering position relative to said discharge openings of the wash arm.

3. In a washing machine of the character described, a hollow stem member, a wash arm rotatably mounted and axially movable on said stem and adapted to be rotated and moved axially by the reaction of fluid expelled therefrom, a rinse arm separately mounted on said stem for rotation thereon and also adapted to be rotated by the reaction of fluid expelled therefrom, and clutch means interposed between said wash arm and said rinse arm, said clutch means being normally disengaged to provide for rotation of said rinse arm entirely independent of said wash arm and being operable upon said axial movement of said wash arm to effect rotation of both of said arms with the rinse arm lying in a vertical plane that is displaced from a vertical plane 35 passing through the wash arm.

4. In a washing machine of the character described, a hollow stem member, a rinse distributor having a laterally extending arm provided with discharge outlets rotatably mounted on said stem and adapted to be rotated by the reaction of fluid expelled therefrom, a wash distributor having a laterally extending arm provided with discharge outlets, means for mounting said wash distributor on said stem for limited axial movement in response to the introduction of fluid thereinto and for rotation in response to the reaction of fluid expelled therefrom, and means operative upon said axial movement of said wash distributor for effecting positive engagement and rotation of both distributors with the laterally extending arm of said rinse distributor maintained in a non-interfering position relative to the discharge outlets of said wash distributor.

5. A washing device of the character described comprising a stem, a rotatable wash distributor and a separately rotatable rinse distributor mounted on said stem, means supporting said distributors for relative movement towards and away from each other axially of the stem, means for rotating each one of said distributors in response to fluid being supplied thereto, cooperating driving parts carried respectively by said distributors, and means effective upon axial movement of the distributors relative to each other for causing positive engagement of said driving parts and rotation of both distributors in response to fluid being supplied to the other of said distributors.

6. A washing device of the character described comprising a stem, a rotatable wash distributor and a separately rotatable rinse distributor coaxially mounted on said stem, means including a resilient member for normally maintaining said wash distributor in a position spaced from and

out of contact with said rinse distributor to provide for rotation of the rinse distributor independently of the wash distributor, said resilient member providing for movement of said wash distributor towards said rinse distributor upon introduction of a wash fluid thereto, and means operative upon said movement of the wash dis-

tributor for connecting said distributors together for joint rotation with the rinse distributor maintained in a predetermined non-interfering position relative to the discharge of wash fluid from the wash distributor.

5
GERALD B. FOX.
